DESIGN FOR A MOLDED BOTTLE CAP OR LIKE ARTICLE

Ambrose D. Paull and James S. Kelly, Wheeling,
W. Va., assignors to Wheeling Stamping Company, Wheeling, W. Va., a corporation of West Virginia

Application January 4, 1938, Serial No. 74,086

Term of patent 14 years

To all whom it may concern:

Be it known that we, Ambrose D. Paull and James S. Kelly, both citizens of the United States and both residing at Wheeling, Ohio County, State of West Virginia, have invented a certain new, original, and ornamental Design for a Molded Bottle Cap or Like Article, of which the following is a specification, reference being had to the accompanying drawing, forming a part thereof.

In the drawing:

We claim:

The ornamental design for a molded bottle cap or like article, as shown.

AMBROSE D. PAULL.
JAMES S. KELLY.
